CLAIM

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 in FIG. 3, in which the internal mechanism is omitted;

FIG. 10 is a perspective view thereof showing the notebook computer in the usage status; and,

FIG. 11 is another perspective view thereof showing the notebook computer in the usage status.

The even-dashed broken lines shown in the drawings illustrate portions of the notebook computer that form no part of the claimed design.

1 Claim, 9 Drawing Sheets
